UNITED STATES PATENT OFFICE

FELIX KÄPPLER, OF DRESDEN, GERMANY

MATCH

Application filed September 19, 1928. Serial No. 308,998.

This invention relates to a process for making matches of rectangular form from strips of pasteboard, the breadth of which corresponds to the length of the matches, in which the strips of pasteboard are cut out into the form of teeth along both longitudinal edges, and the breadth of these rectangular notches, as well as the breadth of the gaps located between each two adjacent rectangular teeth, correspond to the breadth of the matches, and in which moreover, opposite to each tooth on one edge of a strip of pasteboard there is a gap on the other edge, so that when the strips are subsequently divided by cuts extending at right angles to the length of the strip, at distances which correspond to the breadth of a tooth, individual matches are produced, the heads of which are turned alternately to the left and to the right of the length of the strip. Strips of the aforementioned kind for the manufacture of matches are in themselves known.

The novelty of the present invention consists in the fact that the strips toothed on both sides are manufactured from a broad strip several times as wide as the toothed strips by simultaneous subdivision of the broad strip into a plurality of unit strips extending parallel to one another side by side and engaging in one another by their teeth without waste along the adjacent lines of separation, whereupon these unit strips still advancing and interengaging in one another in the position obtained in the subdivision of the broad strip, are first fed to a paraffining position, at which they are saturated with liquid paraffin, whereupon moving further they pass to several positions at which the separation of the individual strips proceeds by releasing their mutual tooth engagement, each unit strip being transferred into a direction of movement which is altered in relation to the direction of the adjacent unit strip, so that finally each individual strip advances independently of the others and each passes to a position at which all its teeth are equipped with ignition material, whereupon, after the drying of the latter at a further position,

the individual strips are subdivided into individual matches.

In the accompanying drawings,

Fig. 1 shows a plan of the strip of material, which is first subdivided by cuts into a plurality of narrower strips, three in the present case, with serrations along both longitudinal edges, the teeth of one edge engaging in the gaps between the teeth of an adjacent strip, and the projecting stick ends being subsequently equipped with match heads, after which the subdivision of the strips into separate matches is effected,

Fig. 2 shows in side elevation the arrangement and connection of the individual machines through which the strip of material has to travel from the roll right to the complete drying of the match heads,

Fig. 3 shows diagrammatically in perspective the course of the strips of material when travelling through the machine which provides the projecting ends of the match sticks with ignition material,

Fig. 4 shows in cross section a portion of the drying device through which the strip has to pass, and

Figs. 5 and 6 show in cross section and in plan respectively various constructional details.

The band of material 1 unwinding from the roll 2 first traverses, on a machine A, a printing press 3 of any desired known construction, in which it is provided with suitable inscriptions, such as advertising matter for example. The band of material then passes through a preferably heated pair of feed rollers 4, a paraffining device, not forming part of the present invention, consisting of two rollers 5, of which the lower one dips into a vessel 6 containing liquid paraffin, the band of material being saturated with paraffin, whereupon it passes through a pair of feed rollers 7 corresponding to the rollers 4.

The band now passes into a stamping machine B. This may again be of known construction. It preferably corresponds in its various details to the machine illustrated in German Patent Specification No. 461,737. The feeding of the band of material in

the stamping machine B proceeds stepwise, this being made possible by a ratchet and pawl gear 8, 9, which is connected by a connecting rod 10 and a crank 11 with a fly-wheel shaft 12, which, through the medium of lifting rods 13 alternately raises and lowers a tool holder 14. In the stamping machine and strip of material is divided by suitably designed tools into a plurality of strips 1^a, 1^b, 1^c and so forth (see Fig. 1), serrated on both edges, and then forms a loop 1^a and passes stepwise to a pair of feed rollers 15 on a machine C. On the machine C there takes place the application of ignition material 1^e to the projecting ends of the match sticks on both sides of all the bands formed by subdividing the original band of material 1 into narrower strips 1^a, 1^b, 1^c and so forth.

For this purpose there are provided upon the machine C vessels 16, 17 and 18 arranged opposite to one another in pairs on both sides of the edges of each of the serrated strips 1^a, 1^b, 1^c and so forth, and these vessels contain a pasty mass of ignition material into which there dips the lower peripheral portion of pairs of discs 19, 19^a, 20, 20^a, and 21, 21^a. The discs 19, 19^a, 20, 20^a, and 21, 21^a arranged in pairs with their associated shafts and revolving at the same velocity are arranged at different positions on the machine C but at the same level, and touch the ends of the match sticks with their central peripheral portions projecting out of reach of the associated vessels, at a depth which corresponds to the height of the match heads to be produced thereon. Upon this contact taking place, the ends of the match sticks which bend somewhat towards the side out of the plane of the advancing strips 1^a, 1^b, 1^c, lie flat against the peripheral portion of the discs which come into contact with them, and which in their turn deliver to the ends of the match sticks the ignition material carried by them, so that match heads are produced upon the said ends. The contact of the ends of the match sticks with the discs must take place in succession in such a way that the left-hand and right-hand faces of the ends of the match sticks are smeared with ignition material alternately. This is effected, as shown more particularly in Fig. 2, by the fact that the strips move first in the direction of the transverse line connecting the right-hand lower edge with the left-hand upper edge of the breadth of the strip past the periphery of the strips, whereupon the strips pass over guiding rollers in such a way that at the next contact with the adjacent disc they move forward in the opposite transversely extending line. Thus for example the strip 1^a, after it has passed the pair of feed rollers 15, runs over the guiding roller 22 in a direction ascending obliquely from right to left, to guiding

rollers 23 and 24, and then in an oblique direction ascending from left to right over a guide roller 25 to a pair of feed rollers 26, and from there to the drying apparatus D. The strip 1^b, after leaving the pair of feed rollers 15, runs over guide rollers 27 and 28, at first ascending obliquely from right to left past the disc 20, over guide rollers 29 and 30, and then ascending obliquely from left to right past the disc 20^a and over the guide rollers 31 to the pair of feed rollers 26 and from there to the drying apparatus D. The strip 1^c, after passing the pair of feed rollers 15, and the guide roller 27, passes over guide rollers 32 and 33, ascends obliquely from right to left and passes over rollers 34 and 35, and then ascends obliquely from left to right and passes over a guide roller 36 to the pair of feed rollers 26 and from there, to the drying apparatus D.

With the introduction of the strips 1^a, 1^b and 1^c into the pair of feed rollers 15, three armouring strips 37, 38 and 39 run in an upward direction over a guiding roller 40, and, coming in a downward direction over a guiding roller 41, three supplementary armouring strips 42, 43 and 44, all of which run between the feed rollers 15. The strips 39 and 42 place themselves upon the strip 1^c from below and from above respectively, the strips 38 and 43 upon the strip 1^b, and the strips 37 and 44 upon the strip 1^a, and then move on holding these strips between them in the manner already described, right to the exit point formed by the pair of rollers 26. At this exit point the bands 42, 43 and 44 run away over the upper roller 15 and past a tensioning roller 45 and over a guide roller 41 downwards, and the armouring strips 37, 38 and 39 run over tensioning rollers 46 and 47 downwards, until both pairs of all the armouring bands re-assemble at the introduction point 15. The tensioning rollers 45, 46 and 47, by means of an adjustable displacement, provide for the strips of material 1^a, 1^b and 1^c to remain nipped by the armouring bands throughout their entire paths of movement and contact, so that all the resistances to movement are taken up by the armouring bands and compensated for in their tensile stresses.

The armouring bands are narrower than the strips of material 1^a, 1^b and 1^c. They only cover the strips of material to a breadth which leaves the serration of the strips of material completely free. In order moreover to guard against a transverse displacement of the armouring strips in relation to the strips of material lying between them, the armouring strips are provided at the centre and at suitable distances apart with pins or embossed projections 48 and 49, which engage in grooves 15^a and 26^a turned in the inlet and outlet rollers and in the

guiding and tensioning rollers provided for the armouring bands.

The drying apparatus D consists of a casing 50, in the interior of which, near the side walls, are rotatably supported superposed guiding rollers 51 and 52. Round each pair of guiding rollers 51 and 52 passes an endless armouring band 53, the number of armouring bands corresponding to the number of strips of material 1^a, 1^b and 1^c, and the breadth of each armouring band being such as to leave free the serrations on the strips of material. These armouring bands, like the armouring bands 37, 38 and 39, 42, 43 and 44 already described, have projections or pins 54 projecting inward here and there, which engage in annular grooves 50^a and 51^a in the guiding rollers, and thus prevent a transverse displacement of the bands. In grooves 55 or ledges on the walls of the casing, rotatable tensioning rollers 56, 57 can be adjusted and secured in position, and these in their turn are provided with annular grooves 56^a, 57^a for engagement with the projections or pins 54 on the armouring bands 53, thus rendering it possible to tension the opposite elements of two adjacent armouring bands advancing in the same direction in such a manner that the strips of material 1^a, 1^b and 1^c advancing between them at the same velocity remain firmly nipped.

The introduction of the strips of material 1^a, 1^b and 1^c into the drying apparatus D is effected at the point 58 of the casing 53. The entering strips of material, which remain so far from one another that the serrations, or the match heads applied to the ends of the serrations, do not touch one another, pass over a guide roller 59 into the uppermost pair of guiding rollers 51, between the armouring bands 53 passing round the same, and then, advancing with the bands, pass to the uppermost pair of outlet rollers 52. Here the strips of material change their direction of motion into the opposite direction and travel through the entire space of the drying casing 50 in a serpentine course, until they leave it near the bottom of the side wall opposite to the entrance side, and are led to a punching machine, where they are cut up into separate matches.

The drying chamber 50 may for example be electrically heated, and is moreover provided with ventilating devices, which convey the vapours that arise into the open air.

What I claim is:—

1. A process for the manufacture of matches of rectangular form from strips of pasteboard and the like from the breadth of which is a multiple of the length of the matches to be made, comprising dividing the broad strip into unit strips the breadth of which is substantially equal to the length of the matches to be made, the dividing lines being in the form of rows of rectangular teeth with rectangular gaps between them, the breadth of each tooth and the breadth of each gap being equal to the breadth of the individual matches to be made, the teeth and gaps along the edge of one unit strip meshing with the gaps and teeth along the edge of the adjacent unit strip so that no material goes to waste, and the teeth and gaps along one edge of each unit strip being opposite to gaps and teeth respectively along the other edge of the same unit strip, saturating the broad strip with liquid paraffin, separating the unit strips from one another along the lines of interengaging teeth, applying ignition material to the projecting teeth along both edges of each unit strip, drying the ignition material, and dividing up the unit strips by transverse cuts at distances equal to the breadth of a tooth to obtain individual matches with their heads projecting to the right and left alternately. 70 75 80 85 90

2. A process for the manufacture of matches of rectangular form from strips of pasteboard and the like, the breadth of which is a multiple of the length of the matches to be made, comprising dividing the broad strip into unit strips the breadth of which is substantially equal to the length of the matches to be made, the dividing lines being in the form of rows of rectangular teeth with rectangular gaps between them, the breadth of each tooth and the breadth of each gap being equal to the breadth of the individual matches to be made, the teeth and gaps along the edge of one unit strip meshing with the gaps and teeth along the edge of the adjacent unit strip so that no material goes to waste, and the teeth and gaps along one edge of each unit strip being opposite to gaps and teeth respectively along the other edge of the same unit strip, saturating the broad strip with liquid paraffin, separating the unit strips from one another along the lines of interengaging teeth, applying ignition material to the projecting teeth along both edges of each unit strip, drying the ignition material, and dividing up the unit strips by transverse cuts at distances equal to the breadth of a tooth to obtain individual matches with their heads projecting to the right and left alternately. 95

3. A process for the manufacture of matches of rectangular form from strips of pasteboard and the like from the breadth of which is a multiple of the length of the matches to be made, comprising dividing the broad strip into unit strips the breadth of which is substantially equal to the length of the matches to be made, the dividing lines being in the form of rows of rectangular teeth with rectangular gaps between them, the breadth of each tooth and the breadth of each gap being equal to the breadth of the individual matches to be made, the teeth and gaps along the edge of one unit strip meshing with the gaps and teeth along the edge of the adjacent unit strip so that no material goes to waste, and the teeth and gaps along one edge of each unit strip being opposite to gaps and teeth respectively along the outer edge of the same unit strip, saturating the broad strip with liquid paraffin, guiding each unit strip between two endless armouring bands consisting of flexible material of ample tensile strength such as steel, which cover both its surfaces for about the breadth of the untoothed central portion of the strip and advance with the strip at the same speed, changing the direction of motion of the unit strips relatively to one another and thereby separating the unit strips from one another along the lines of interengaging teeth, applying ignition material to the projecting teeth along both edges of each unit strip, drying the ignition material, and dividing up the unit strips by transverse cuts at distances equal to the breadth of a tooth to obtain individual matches with their heads projecting to the right and left alternately. 100 105 110 115 120 125

3. A process for the manufacture of matches of rectangular form from strips of

pasteboard and the like the breadth of which is a multiple of the length of the matches to be made, comprising dividing the broad strip into unit strips the breadth of which is substantially equal to the length of the matches to be made, the dividing lines being in the form of rows of rectangular teeth with rectangular gaps between them, the breadth of each tooth and the breadth of each gap being equal to the breadth of the individual matches to be made, the teeth and gaps along the edge of one unit strip meshing with the gaps and teeth along the edge of the adjacent unit strip so that no material goes to waste, and the teeth and gaps along one edge of each unit strip being opposite to gaps and teeth respectively along the other edge of the same unit strip, saturating the broad strip with liquid paraffin, guiding each unit strip between two endless armouring bands consisting of flexible material of ample tensile strength such as steel, which cover both its surfaces for about the breadth of the untoothed central portion of the strip and advance with the strip at the same speed, guiding the endless armouring bands round guiding rollers arranged opposite to one another in pairs at the point where the armouring bands first come into contact with the strips and at the point where the armouring bands pass out of contact with the strips, the said guiding rollers bearing firmly enough against the armouring bands to cause the said armouring bands to nip the unit strips, changing the direction of motion of the unit strips relatively to one another and thereby, separating the unit strips from one another along the lines of interengaging teeth, applying ignition material to the projecting teeth along both edges of each unit strip, drying the ignition material, and dividing up the unit strips by transverse cuts at distances equal to the breadth of a tooth to obtain individual matches with their heads projecting to the right and left alternately.

4. A process for the manufacture of matches as claimed in claim 15, further comprising positively preventing the armouring bands from slipping transversely to the direction of motion of the strips.

5. A process for the manufacture of matches of rectangular form from strips of pasteboard and the like the breadth of which is a multiple of the length of the matches to be made, comprising dividing the broad strip into unit strips the breadth of which is substantially equal to the length of the matches to be made, the dividing lines being in the form of rows of rectangular teeth with rectangular gaps between them, the breadth of each tooth and the breadth of each gap being equal to the breadth of the individual matches to be made, the teeth

and gaps along the edge of one unit strip meshing with the gaps and teeth along the edge of the adjacent unit strip so that no material goes to waste, and the teeth and gaps along one edge of each unit strip being opposite to gaps and teeth respectively along the other edge of the same unit strip, saturating the broad strip with liquid paraffin, separating the unit strips from one another along the lines of interengaging teeth, carrying each unit strip past two discs, one in contact with each toothed edge, carrying each unit strip past two further discs at a different angle, one in contact with each toothed edge, applying ignition material in paste form to the peripheries of the discs, for transfer to the toothed edges, drying the ignition material, and dividing up the unit strips by transverse cuts at distances equal to the breadth of a tooth to obtain individual matches with their heads projecting to the right and left alternately.

In testimony whereof I have signed my name to this specification.
